United States Patent Office

Des. 206,330
Patented Nov. 29, 1966

206,330

SUPPORT BASE FOR A COMBINED TABLE AND SEATING UNIT

George Kasparian, Los Angeles, Calif., assignor to Kasparians, Inc., Los Angeles, Calif., a corporation of California

Original design application Feb. 11, 1964, Ser. No. 78,598.
Divided and this application Oct. 22, 1965, Ser. No. 430

Term of patent 14 years

(Cl. D33—14)

Fig. 1

FIGURE 1 is a perspective view of a support base for a combined table and seating unit embodying my novel design;

This application is a division of my earlier application Serial No. D.78,598, filed February 11, 1964, and now abandoned.

I claim:

The ornamental design for a support base for a combined table and seating unit, substantially as shown and described.
